PRINTING APPARATUS

Milton Reynolds and Harold G. Barrett, Chicago, Ill., assignors to Printasign Corporation of America, Chicago, Ill., a corporation of Illinois

Application October 6, 1943, Serial No. 505,096

15 Claims. (Cl. 197—2)

This present invention relates generally to printing apparatus and is more particularly described in connection with that type of printing apparatus designed primarily to print cards for sign or placard forming purposes, and comprises a movable type supporting member which is rotated and shifted in the same plane to bring different types into printing position and is then depressed to effect the printing of a selected character.

An important object of the invention is to provide a printing apparatus of this kind which is an improvement upon and may be operated more easily and quickly than previous apparatus of this same general type.

Another object of the invention is to provide an improved operating lever and connected mechanism for simplifying the card feeding operation at the conclusion of each printing operation.

A further object of the invention is to provide an improved means for supporting and operating the type and characters for printing operations.

A further object of the invention is to provide an improved inking device and a simple selective device for operating it.

A still further object of the invention is to provide a sign or placard printing apparatus which occupies a minimum space and may be produced at a comparatively low and reasonable cost.

Other objects of the invention and the various advantages and characteristics of the present printing apparatus will be apparent from a consideration of the following detailed description.

The invention consists in the several novel features which are hereinafter set forth and are more particularly defined in the claims at the conclusion hereof.

In the drawings which accompany and form a part of this specification or disclosure and in which like numerals of reference denote corresponding parts throughout the several views:

Fig. 1 is a plan view of a printing apparatus embodying this invention;

Fig. 2 is a section taken on the line 2—2 of Fig. 1;

Fig. 3 is a detail perspective illustrating a part of the feed controlling mechanism;

Fig. 4 is a sectional view taken on the line 4—4 of Fig. 2;

Fig. 5 is a sectional view taken approximately on the line 5—5 of Fig. 2 showing the position of some of the operating mechanism just prior to the printing operation;

Fig. 6 is a view similar to Fig. 5 showing the same parts at the time of printing;

Fig. 7 is a detail section illustrating a modification of a printing type;

Fig. 8 is a fragmentary plan view of the printing type carrier and holder;

Fig. 9 is a sectional view of one of the carrier parts shown in Fig. 8;

Fig. 10 is a sectional view of the type holder and spacing plate as shown in Fig. 8;

Fig. 11 is a sectional view illustrating the one-way clutch mechanism;

Fig. 12 is a side elevation with parts and sections further illustrating the one-way clutch mechanism;

Fig. 13 is a perspective of one of the supporting parts of the clutch mechanism; and

Fig. 14 is a perspective of the clutch dog of the clutch mechanism.

The printing apparatus shown in the drawings constitutes a preferred embodiment of the invention which is designed or adapted primarily to

print cards in forming signs or placards. It comprises a movable member which carries the type adapted to be shifted and rotated in the same plane to bring different type into printing position and then depressed to effect the printing. The depression of the type carrier also causes the operation of spacing mechanism which advances the card or paper being printed a space or distance in accordance with the width of the letter or character which is printed, it being apparent that some letters or characters are wider and require different spacing than others.

Referring more particularly to the drawings, a hollow card supporting base 16 is preferably made of sheet metal which provides a flat platen or top surface 17 for receiving a sheet or card 18 to be printed. Mounted centrally at the back of the base is a hollow supporting arm 19 also preferably formed of sheet metal, the free end extending

40 forwardly approximately to the center of the top surface of the base. The card or sheet 18 to be printed rests flatly on top of the base which is slightly larger than four times the size of the sheet to be printed since it must be moved from left to right and from top to bottom with respect to the printing mechanism in order to cover the entire sheet. Each sheet to be printed is held at its lower edge in a movable carrier comprising a card retaining strip 20 with spring paper retaining

45 clips 21 at the edge for holding the paper against the strip, the carrier being movable below a channel strip 22 which forms a part of the carriage, mounted at its ends for movement toward and from the printing mechanism by

50 55

means of side slots 23 at the edges of the top 17 of the base.

The printing mechanism is located at the extremity of the hollow arm 19 and comprises a rotary type carrier which is mounted for movement longitudinally of the arm and also for a depressing or printing movement. This type carrier comprises a hollow circular member 24 with a transverse web 25 extending therefrom, supporting opposite front and rear projections 26. Each projection carries a mounting wheel or roller 27 attached by means of a shoulder screw 28, and each roller has an angular edge 29 mounted in corresponding upper and lower angular grooves 30 located in opposite sides of the extremity of arm 19 and extending parallel with the top 17 of the base.

A shouldered stem 31 is inserted through the hollow member 24, and a coil spring 32 is disposed in a recess 33 between the stem and the member, abutting the member at the lower end of the recess and a shoulder 34 on the stem at the top of the recess. Secured to the lower end of the stem by a cross pin 35 is a type carrier 36 having a hub 37 which is resiliently held against the lower end of the member 26 by the spring 32.

At the upper end of the stem is a central bore or recess 38 for receiving the supporting shaft 39, of a letter selecting and spacing guide. This guide comprises a plate 40 held on the shaft by a knob 42 secured to the shaft and having a threaded portion extending centrally through the plate, and a nut 41 engaging the threaded portion and the under side of the plate holding it against a shoulder 43 on the knob.

Near the lower end of the shaft 39 is a transverse slot 39a for receiving a cross pin 31a secured to the upper end of the stem 31 for limiting the movement of the shaft in the recess 38. A coil spring 44 surrounds the shaft 39 and is interposed between an outward flange 45 at the upper end of the stem 31 and the under side of the selector plate 40, the upper end of the spring being seated in a recess between the lower ends of the nut 41 and knob 42. The spring 44 is relatively stronger and harder to compress than spring 32, so that when the carrier stem 31 is moved downwardly by pressure on the knob 42, the flange 45 engages the top of member 24 limiting downward movement of the type carrier. Continued downward pressure on the knob 42 compresses spring 42, allowing a further independent downward movement of shaft 39 into the bore 38 against the spring 44, limited by the engagement of the pin 31a in the slot 39a, which causes a corresponding movement of the selector and operating plate 40, without any relative rotative movement of the plate with respect to the type carrier 36.

The type carrier 36 is preferably circular in form and comprises a number of type openings 46 preferably in radial lines or arrangement, separated by ribs 47. At its outer periphery is a gear 48 for operating an inking device.

A plurality of printing types or characters 49 are attached at one side of a resilient, flexible disc 50 and arranged according to the opening 46 of the carrier. At the opposite side of the disc 50 are stiff contact plates 51 corresponding to each of the opposite types or characters 49. The supporting disc 50 is preferably a resilient sheet of rubber or rubber-like material, and it is mounted at the under side of the carrier 36. A thin mounting plate 52 having openings 53 corresponding to the types 49 and ribs 54 rounded at the top between the openings is applied to and supports

the under side of the type supporting disc 50 and between the types 49. The plate is secured to the carrier 36 by fastening screws 55 at the periphery and a fastening screw 56 at the center.

Partly within the base and partly within the arm 19 is a U-shaped operating lever 57 mounted between its ends upon a cross shaft 58 which has end bearings 59 in the sides of the arm 19. The upper end of this lever extends below the transverse web 25 of the supporting member 24, and the lower end extends within the base 16.

At the upper end of lever 57 is an extension 60 with a connecting offset 61 to bring the extension close to the printing position at the front and rear center line of movement of the type carrier. Mounted on a pivot 62 adjacent the upper end of the extension 60 is a control member 63 with a pointed extremity 64. The pivot 62 is in the form of an extending screw having a projecting head 65, and at the lower end of the extension 60 is another similar headed screw 66. An operating bar 67 has slots 68 and 69 to mount it for sliding movement on the reduced portions of the mounting screws 65 and 66 and retained by their heads so that it is movable relatively to the extension of the operating lever. At the upper end of the bar is a flat extremity 70 for engaging the under side of the letter spacing guide plate 40, and the lower extremity 71 is slightly reduced but is flat at the end to engage any one of the contact plates 51.

On the upper side of the letter spacing guide plate 40 are letters and characters 72 corresponding to the arrangement of letters or characters in the type carrier 36. At one side of each letter or character is a corresponding slot 73. The width of the slot is sufficient to admit the pointed extremity 64 of the control member 63, and the length of each slot determines the amount that the pointed extremity 64 of the control member can project through the slot. These slots differ in length corresponding oppositely to the widths of the letters, a letter like "I" having a slot of maximum length, and a letter like "W" or "M" having a slot of length corresponding inversely to the comparative width of the letter. The feed is determined by the relative movement between the member 68 and the bar 67, short slots 73 being engaged by the pointed extremity 64 earlier than the long slots and thus producing a relatively longer movement. These slots 73 are called letter spacing slots and they control the letter feeding movement of the printing mechanism so that the card or sheet to be printed is advanced an amount equal to the width of the letter or character printed after the printing of the letter has been effected.

A pivoted and spring pressed control member 63 is provided to insure engagement with the letter spacing slots 73 regardless of the position of its lever 57, and in order to maintain the operating bar in contact with the under side of the letter spacing guide 40 at all times. This is effected by providing a projection 74 at the lower outside end of the member 63 in position to engage a projection 75 from the outer edge of the lever extension 60 which is in the path of the projection 74. Near the lower end of the operating bar 67 is a projection 76 substantially in line with the projection 74 and connected at each end to these projections is a coil spring 77 which tends to hold the projection 74 of the controlling member 63 against the projection 75 and at the same time tends to press the operating bar 67 upwardly in its mounting slots and with respect to the end

of the lever 57 and in contact with the under side of the letter guide 40.

The operating lever 57 is also held upwardly by a spring 18 connected at one end to the lever and at the other end to an adjusting screw 19 extending through the outer casing of arm 19 and having a threaded lock nut or collar 20 outside of the arm in which it is adjustable. Movement of the lever caused by the spring is limited by a projection 20a extending from the lever near its outer end and adapted to engage the under edge of one of the projecting ends of the arm 19, as shown more clearly in Fig. 4.

As shown in Fig. 1, the letters or characters 12 and their corresponding slots 13 occupy only about one-fourth of the surface of the guide plate, but it is understood that the entire surface may be covered with other letters or characters including several varieties of type, numerals or other characters that may be desired.

Printing types 49 may be made of stiff or relatively flexible material, but the contact plate 5, or 51a as shown in Fig. 7, is preferably of metal or other stiff material. As the supporting disc 50 is resilient, the operating bar 67 contacting with the plate will equalize the printing pressure at the face of the type 49 whether the end of the bar 67 is large in comparison with the plate 51 or somewhat smaller than plate 51a, if the face of the printing type is parallel to the surface of the contact plate. By distorting the resilient disc 50 over the rounded ribs 54 of the supporting plate only one type is moved into printing contact, and after such engagement and relief of pressure upon the operating knob 42, the resilience of the disc immediately returns any printing character to its normal position in the carrier.

In order to apply ink to printing types or characters 49, an inking device may be mounted at the front of the arm 19 by means of a bracket 81, secured thereto by screws 82 or other suitable fastening devices, and comprising a hollow stem 83 with an ink receiving hopper 84 at the top closed by a removable lid 85.

Secured to the hopper and projecting above the guide plate 40 in its raised position is a pointer 86 which extends toward the type carrier and designates the letter which is at the printing position when the spacing slot 13 at the right side of each letter is moved to the tip of the pointer as the carrier is moved forward or backward or is rotated, so that the pointer thus designates the letter which is in the printing position to be actuated by the operating bar 67.

A suitable inking device is located at the bottom of the hollow stem 83 and comprises a hollow tube 87 rotatable in the stem with a small gear 88 near its lower end terminating in an arm 89 extending at right angles and comprising a hollow internal feeder with an outside inking pad or wiper 90 of fabric or other suitable material. The hollow tube 87 is held in downward position and may be automatically returned from an inking position by a coil spring 91 which surrounds the tube 87 and is interposed between the gear 88 and the lower end of the hollow stem 83. A shield 92 secured at the lower end of the stem 83 extends below and partially around the inking arm in its normal or inoperative position.

To apply the inking device to the type faces, the type carrier 36 is moved forwardly within its supporting member 24 by pulling the knob 42 forwardly until the gear 48 engages the gear 83. By then turning the knob in a counter-clock-

wise direction, the inking pad or wiper 90 is rotated over the face of the type at the printing position, or all the type which may be in the path of the wiper as indicated more clearly in Fig. 1. The operation of the inking device is thus made selective and optional so that the type faces need not be inked for each printing operation, or if desired, they may be inked before each operation thereof. If the ink is applied to each type face before printing, the pad or wiper would be required only at the end or extremity of the arm 89.

Movable rearwardly from the front of the casing is the paper carriage in which the sheet carrier strip 20 is transversely movable. It has a bottom plate 99 which rests upon the top 17 of the casing and a channel strip 22 is secured thereto and overlies and rests upon the front edge of the strip 20. The carrier strip 20 is held in place under the channel strip by a rib 101 secured along the covered edge and the channel strip is held on the bottom plate 99 by fastening screws 102.

The carriage comprises the bottom plate 99 and the channel plate 22 mounted for front and rear sliding movement upon the base 16 by means of the side slots 23. Connected to the under side of each carriage is a rack 102 at each side below each of the side slots 23 which mesh with pinions 104 on a shaft 103 rotated from one or both sides 30 of the base by a knurled head 105 secured to the shaft and located at the outer edge of the casing.

At the lower end of the lever 57 is a slot 93 engaged by a projection 94 from a collar 95 secured to an angular shaft 96 extending within the casing 16 and mounted for rotation in bearings 97 and 98 at the front and rear of the casing so that the shaft is rocked in opposite directions by the raising and lowering movements of the lever.

The step by step letter spacing movement of the card holding strip 20 is effected from the movements of the rock shaft 96 by means of a one way clutch 106 secured to the under side of the carriage plate 99 and overlying the rock shaft 96. It is movable with the carriage in a longitudinally extending central opening 107 which terminates in front of the printing position as defined by the extremity of the pointer 86. The particular construction of the one way clutch forms no part of this invention but it comprises a bracket 108 secured to and depending from the bottom carriage plate 99 through the opening 107 with an upturned slotted extremity 109 embracing and engaged in a slot of a collar 110 mounted and slidable upon the angular shaft 96. An arm 111 secured to the collar 110 is rocked with the shaft 96 and moves the clutch mechanism different letter spacing distances in accordance with the rocking movement of the shaft.

In the clutch, a pair of plates 115 and 116 have upper projecting ears 117 and 118 to engage above and below the edge of the carrier strip 20 for free sliding movement with respect thereto. Both plates have corresponding notches with one vertical edge 119 and one inclined edge 120. In these notches a clutch dog 112 is mounted for limited angular movement by means of a slot 125 at an end which extends over both plates at the bottoms of the notches. At one edge of the dog is a gripping notch 113 which engages over the edge of the carrier strip 20 and is adapted to grip the strip when inclined thereto but to slide along with the plates when it is in

upright position or at right angles to the strip. A spring 121 is mounted on a projection 122 and has an angular free end which engages the dog 112 tending to press it from an upright position to an inclined position in which the gripping notch 113 engages the strip 20. In the plates 117 and 118 are registering notches 123 through which extend a pin 124 projecting from the end of the arm 111. As the arm is rocked with the shaft 96, the plates 115 and 116 with the dog 112 are moved along the edge of the carrier strip 20, the dog gripping the strip in one direction but moving free of engagement in the other direction.

Then the shaft 96 is moved in a downward direction by the lever 57, the clutch dog 112 is moved freely with respect to the strip and in a direction from left to right of the sheet or placard which is being printed, and when the shaft 96 is returning in the other direction by the movement of the lever, the edges of the notch 113 grip the opposite sides of the edge of the strip 20 and move it together with the sheet or card 18 in a letter spacing direction, and in an amount determined by the length of the letter spacing slot 73.

In order to effect independent movement of the sheet and its carrier in a letter spacing direction, the upper extremity of the clutch dog 112 projects through an opening 114 in the channel plate 22 so that it may be engaged by the fingers and moved in opposite directions in the opening.

With this construction, it will be apparent that that paper or sheet to be printed may be readily moved by the carriage and by the sheet carrier strip 20 to place any portion of it at the printing position which is defined by the extremity of the pointer 86.

In the printing operation, the normal position of the type carrier is in raised position as shown in Figs. 2 and 4. At this time, the printing plunger or operating bar 67 is free from engagement with the under side of the selector and guide plate 40, the lever 57 is in raised position and the control member 63 is at the lower end of the slot 68 of the operating member 67. The type carrier may be freely rotated upon its axis and moved forwardly or rearwardly upon its rollers 21 to bring any desired letter or character into printing position at the extremity of the pointer 86. With practice, this is quickly and easily done so that printing is rapidly effected. The type carrier is then depressed by downward pressure on the knob 42 which moves the operating member 64 downwardly with it until the carrier is stopped by the engagement of the flange 45 with the top of carrier member 24. Continued pressure on the knob further depresses the plate 40 additionally moving the printing or operating bar 67 and engaging its extremity with the contact plate 51 of the letter or character selected, pressing that character out of the plane of the flexible disc 50 and into engagement with the face of the sheet to be printed.

Just before the printing operation is effected by the downward movement of the type carrier, the pointed extremity 64 of the letter spacing control member is projected through the spacing slot 73 an amount corresponding to the letter or character to be printed, the length of the slot determining the exact amount that the lever 57 is moved, which in turn controls the movement of the one way clutch 106. The downward movement of the lever 57 moves the clutch and particularly the clutch dog 112 along the edge of

the paper holding strip 20, a distance corresponding to the length of the letter feeding slot 73, and upon the return movement of the shaft 96, the lever 57 and the dog 112, the sheet holding strip 20 is advanced in letter spacing direction a distance depending upon the width of the letter or character which has just been printed.

If it is necessary to ink the letters or characters at any time, the letter carrier is moved forwardly until the gear 48 engages the pinion or gear 88 of the inking mechanism whereupon it is actuated or operated as previously described.

When printing pressure is relieved upon the knob 42, it is returned to its normal or raised position by springs 44 and 32, the lever 57 is returned by its spring 78, and the operating members 67 and 63 are returned to their normal positions and relations by spring 77. The resilient disc 50 also returns any type to its normal position. The parts are then in position for the next printing operation which is repeated until the desired printing is completed.

This mechanism provides an improved construction and arrangement which occupies a small amount of space, it is composed of a relatively few number of parts which may be produced and operated in a simple manner at a comparatively low and reasonable cost.

The invention is not to be understood as restricted to the details set forth since these may be modified within the scope of the appended claims without departing from the spirit and scope of the invention.

Having thus described the invention, what we claim as new and desire to secure by Letters Patent is:

1. In a printing apparatus, a base for receiving thereon a card or sheet to be printed, an arm extending from the rear of the base forwardly to overlie the card or sheet, a type carrier mounted for rotary and reciprocating movement in the arm, the type carrier including an upper plate and a spaced lower resilient disc with types mounted at the under side thereof, a movable operating member between the plate and disc at the printing point for engaging the under side of the plate and the top of the disc opposite any one of the types movable to press a type into engagement with a card or sheet when the plate is moved downwardly.

2. In a printing apparatus, a type carrier and means mounting it for rotary and reciprocating type selecting movement, the carrier comprising an upper plate and a spaced lower resilient disc having types at the under side thereof, an operating bar mounted below the plate and above the disc, and means including the plate for moving the bar into engagement with the disc at the back of any of the types and for depressing the disc and a type out of the plane of the disc for effecting the printing operation.

3. In a printing apparatus, a base for receiving a card thereon to be printed, an arm secured to the base and extending forwardly over the card from the rear of the base, a type carrier mounted for reciprocating and rotary type selecting movement in the free end of the arm, the type carrier comprising an upper type selecting plate and a spaced lower resilient disc with types at the under side thereof, a compressible mounting for the disc, a type operating bar between the plate and disc movable by the plate to engage the flexible disc at the side opposite the type, and means for depressing the plate with respect to the disc for

moving the bar and deflecting a selected printing type to engage the card below it.

4. In a printing apparatus, a sheet supporting base; an arm extending from the rear of the base forwardly over a sheet to be printed, a type carrier mounted in the free end of the arm for rotary and reciprocating movement, the type carrier including a resilient deflectable disc with types on the under side thereof, a plate also movable with the carrier, means for additionally moving the plate with respect to the type carrying disc, and a plunger mounted for movement with the type carrier between the disc and the plate and engageable with the plate and the depressible disc for deflecting a selected type out of the plane of the disc and to engage a sheet on the base to be printed.

5. In a printing apparatus, a base for receiving thereon a sheet to be printed, an arm extending forwardly from the rear of the base to overlie a sheet to be printed, a type carrier mounted at the free end of the base for rotary and reciprocating type selecting movement, the carrier comprising a resilient disc having types to be printed at the under side of the disc, an operating plate mounted for movement with the disc, means for moving the plate an additional distance toward the disc, an operating bar disposed between the disc and the plate mounted for movement in a vertical direction at the printing point, the plate engaging the bar to move it downwardly with the disc, and the plate moving the bar an additional distance deflecting the disc to move the type in printing engagement with the sheet on the base.

6. In a printing apparatus, a base for receiving thereon a sheet to be printed, an arm extending from the rear of the base forwardly to overlie a sheet at the printing point, a type carrier mounted for rotary and reciprocating type selecting movement in the free end of the arm, the type carrier comprising a flexible disc with printing types at the under side thereof, a plate movable with the carrier and disc and positioned above the arm, means for mounting the plate for a depressible printing movement with respect to the disc, and an operating bar interposed between the disc and the plate and movably engaged by the plate to depress the disc and apply the types to the sheet at the printing point.

7. In a printing apparatus, a base for receiving a sheet to be printed thereon, an arm extending from the rear of the base and overlying a sheet at the printing point, a type carrier mounted for rotary and reciprocating movement at the outer end of the arm, the carrier comprising a flexible disc with types at the under side thereof, an operating plate movable with the carrier and disposed above the arm, resilient means for depressibly mounting the disc and the plate in the carrier, an operating bar interposed between the disc and the plate at the printing point, a pointer extending over the plate at the printing point to designate the character which is at the printing point, and means for further depressing the plate to apply the operating bar to the disc when the carrier is depressed.

8. In a printing apparatus, a base for supporting a sheet to be printed thereon, a type carrier and means mounting it for rotary, reciprocating and depressible movement in a position above the base, the carrier comprising a resilient disc with types on the lower surface thereof, a plate movable with the disc and having type designations on the upper face thereof, a pointer for designating the printing character at the top of the plate

which corresponds to the printing type at the bottom of the disc, means to separately depress the plate with respect to the type carrying disc, an operating bar located at the printing point between the disc and the plate and engaged by the plate to move it downwardly and further depressed by the plate to deflect the disc for moving any selected type into printing engagement with a sheet on the base.

10. A printing apparatus, comprising a base for receiving thereon a sheet to be printed, a type carrier movably mounted above the base for rotary, reciprocating and depressible movement, the type carrier comprising a circular bottom member, a type carrying disc mounted in the member having types projecting at the bottom therefrom, a type selecting plate at the top of the carrier, an operating bar mounted at the printing point between the disc and the plate and movable thereby and therewith to effect a printing movement, and an inking device comprising a wiper engaged by the said type carrying member when it is reciprocated in one direction and then rotated to apply ink to the printing face of a type in the printing position.

15. 10. A printing apparatus comprising a base for receiving a sheet thereon to be printed; a type carrier movably mounted for rotary and reciprocating movement to place any one of a plurality of selected types in a printing position, the carrier comprising a rotary type carrying member having a gear at its outer periphery, and types projecting at the bottom thereof, an inking device having a rotary inking arm and a gear on the inking arm to engage the gear of the type carrying member when it is moved in a forward direction, the type carrying member being rotatable to rotate the inking device arm over the printing face of the types in an arc including the printing position; and means for applying the type when inked to a sheet on the platen.

20. 11. In a printing apparatus, a base for receiving thereon a sheet to be printed, an arm secured to the rear of the base and extending forwardly over a sheet at the printing position, a type carrier movably mounted in the free end of the arm for rotary and reciprocating movement to place any one of the types in printing position, means mounting the type carrier in the arm for depressible printing movement, the carrier comprising a flexible type supporting disc, an operating plate spaced above the disc, means for mounting the plate at the top of the carrier for separate depressible movement with respect to the disc, and an operating bar interposed between the type and the plate and movable by the additional depression of the plate into engagement with any one of the selected types carried by the disc.

25. 12. In a card printing apparatus, a type carrier comprising a flexible and resilient disc, a plurality of types secured to the lower printing face thereof, a plate on which the disc is mounted having openings corresponding to each of the types, solid back plates secured to the disc at the side opposite each of the types, an operating bar to engage the plate of any of the types and deforming the disc out of the plane thereof to evenly apply the printing type to a printing surface below the disc.

30. 13. A printing apparatus comprising a base for receiving a sheet to be printed thereon, a type carrier and means for mounting it for rotary and reciprocating movement above the base, the type carrier comprising a flexible and resilient

disc with type secured to the lower face thereof and a pressure plate secured to the opposite side of the disc for each of the types, means for depressibly mounting the type carrier for movement toward and from the face, an operating bar located at the printing position for engaging the plate of any type moved thereunder, stop means for limiting the movement of the disc to a position above the sheet to be printed and means for moving the bar to engage the back plate of a selected type for deflecting a portion only of the disc so that the corresponding type will be moved into printing engagement with the sheet to be printed.

14. In a printing apparatus, a base for receiving thereon a sheet to be printed, a sheet carriage movable in the base including a transversely movable sheet carrier, a variable clutch for engaging the sheet carrier, an operating shaft for the clutch, an arm secured to the base and projecting forwardly over a sheet at the printing position, a type carrier movably mounted in the arm for rotary and reciprocating type selecting movement, the carrier comprising a resilient deflectible disc in which the types are mounted, an operating plate depressible with respect to the carrier disc, an operating bar mounted between the disc and the plate at the printing point and movable by the plate to engage the disc and an operating arm lever pivoted in the arm having a crank connection with the shaft at one end, and a lost motion connection with the operating bar at the other end, the operating plate having slots therein corresponding to the widths of each of the letters of the disc, and a control member mounted on the lever adjacent the operating bar and entering the slot of any selected letter a variable amount to determine the letter spacing movement of the operating lever.

15. In a printing apparatus, a hollow base for receiving thereon a sheet to be printed, a carriage movable forward and back on the base having a sheet engaging carrier transversely movable in the carriage, a variable spacing clutch to

engage the sheet carrier, operating means for the clutch including a rock shaft, an arm mounted at the rear of the base and extending forwardly over the sheet at the printing position, a lever mounted in the base of the arm and having opposite extremities one engaging the rock shaft and the other end having an angular extension with a pointed controlling member pivotally connected thereto, an operating bar having a pin and slot connection to give it a limited movement with respect to said operating member, a spring between the operating member and the bar tending to hold the operating member in upright position and the bar at the lower end of its slots, a type carrier and means for mounting it for rotary and reciprocating movement in the end of the arm, the carrier comprising a resilient disc, and an operating plate spaced apart and on opposite ends of the operating bar, the resilient disc having types at the lower side thereof and the plate having corresponding designations of the types at the lower side of the disc, and the plate having slots therein corresponding to each of the type indications, the slots adapted to be entered by the said operating member depending upon the length of the slot, means for mounting the disc and plate for a joint depressing movement, and means for additionally depressing the operating plate to engage the operating bar with the disc for printing any selected type, stop means for limiting the downward movement of the type carrier, stop means for limiting the upward movement of the operating lever, a spring tending to hold the operating lever in its uppermost position and the entry of the operating member into the slot controlling the extent of movement of the sheet advancing clutch in the return movement of the operating lever upon the return movement of the type carrier and the operating plate to their original positions.

MILTON REYNOLDS.
